UNITED STATES PATENT OFFICE.

DAVID H. JARRARD, OF TALLADEGA, ALABAMA.

GATE.

SPECIFICATION forming part of Letters Patent No. 244,611, dated July 19, 1881.

Application filed May 4, 1881. (No model.)

To all whom it may concern:

Be it known that I, DAVID H. JARRARD, of Talladega, in the county of Talladega and State of Alabama, have invented a new and valuable Improvement in Gates; and I do hereby declare that the following is a full, clear, and exact description of the construction and operation of the same, reference being had to the annexed drawings, making a part of this specification, 10 and to the letters and figures of reference marked thereon.

Figure 1 of the drawings is a representation of side view of my improved gate. Fig. 2 is a top or plan view of the same, and Figs. 3 and 15 4 are detail views.

This invention has relation to turning and sliding gates; and it consists in the construction and novel arrangement of the recessed supporting-post and its hooks, the hinge plates 20 or boards, center roller, and end eyebolts; also, in connection therewith, the rolling latch and drop-latch, arranged at opposite ends of the gate, and the slotted lock-plate, all as herein-after shown and described.

25 In the accompanying drawings, the letters A, A' designate the end gate-posts which carry the latches, and B is the supporting hinge-post, arranged between the end posts, and usually a little nearer one than the other. It 30 is located a little in rear of the gate C, which extends, when fully closed, from one gate-post, A, to the other, A', as shown. Recesses a a are formed in the inner corner of the post B obliquely, and in these recesses are the oblique hooks b b, which are turned toward each other, the upper hook being turned down and the 35 lower hook upward. By this construction the hooks or hinge-pintles are brought as near as possible to the center of the post B.

40 The gate C is constructed of horizontal bars c c' and uprights d d', and is provided with a roller-hinge, D, which is formed of side plates e, perforated at the center to form journal-bearings for the journals of the roller E, which 45 is designed to fit between the middle bars, c', of the gate, said bars passing between the side plates or boards, e, of the hinge-body. At their ends the plates or boards e are perforated for the passage of the eyebolts g, which are 50 provided with washers h and nuts k, and serve to secure the parts of the hinge together, and

being engaged with the hooks b as the hinge-eyes, whereby the gate is connected to the post B, and on which the gate depends in turning. The upright d is arranged near, but at one side 55 of, the middle of the gate, as shown in the drawings, and serves as a stop to prevent the gate from being pulled far from its point of balance in sliding it forward for turning on its hinge.

60 The rear gate-post, A, is provided with a rolling latch, l, consisting of a sleeve having a cylinder-body, on which the gate-bar bears, and a conical end, n, which serves as a stop and inclined plane, said sleeve being pivoted 65 on the pin p, which is secured in the gate-post.

F is a horizontally-slotted lock-plate, which is designed to slide on a pin or screw, q, secured to the upright d' of the gate, and rests 70 by its lower edge on the lowermost of the bars, c'. Between this lock-plate and the upper bar, c', which rests on the roller-latch, is a space sufficient only for the cylinder portion of said latch, so that when the lock-plate is pushed 75 forward or into the gate it will pass under said latch and behind its conical head n, and will prevent the gate from being lifted to unlatch it at this end. When the slide-plate F is pushed in the opposite direction it passes from under 80 the roller-latch, so that the gate can be lifted. At the other end of the gate is secured rigidly an upturned hook, v, which projects beyond the end of the gate, to enter, when the gate is closed, a recess, w, in the front gate-post, 85 A', across the face of which extends the lower bent end of the drop-latch G. This latch consists of a rod the main length of which extends upward through a guide or staple, s, to form a handle, the lower end being transversely arranged across the recess w, and extending 90 through the lower guide or staple, s', which is arranged vertically, as shown, and is of sufficient length to allow the latch to have the necessary play with reference to the hook v. 95

In this manner is formed a balanced gate of simple construction. When used as a slide-gate only it moves on the hinge-roller and roller-latch. When the wide portion of the gateway is to be used the rear end of the gate 100 is lifted off the roller-latch. This action depresses the hook v and unlatches the front end

of the gate, so that it can be readily turned on the hooks *b b* to extend at right angles to the gateway.

Having described this invention, what I claim, and desire to secure by Letters Patent, is—

1. The combination, with the gate-post *B*, having the recess *a* and oblique hooks *b* turned toward each other, of the horizontal gate-bars *c' c'*, and the perforated hinge plates or boards *c*, center roller, *E*, eyebolts *g*, and nuts *k*, substantially as specified.

2. The combination, with a sliding gate and its middle hinge, *D*, of the roller-latch *l* at one end, and the drop-latch *G* and upturned hook *v* at the other end, substantially as specified.

3. The combination, with the horizontal bars *c' c'* of the gate and the latch *l*, engaging the uppermost of said bars, of the slotted lock-plate *F*, attached to the gate by the pin *q*, on 20 which it slides, and resting on the lower of said bars, substantially as specified.

In testimony that I claim the above I have hereunto subscribed my name in the presence of two witnesses.

DAVID HENRY JARRARD.
